Patented Dec. 19, 1922.

1,439,605

UNITED STATES PATENT OFFICE.

MORTIMER BYE AND LEWIS H. CARLSON, OF DETROIT, MICHIGAN, ASSIGNEES TO FREDERICK STEARNS & COMPANY, OF DETROIT, MICHIGAN, A CORPORATION OF MICHIGAN.

MEDICINAL PREPARATION.

No Drawing.

Application filed June 6, 1921. Serial No. 475,500.

To all whom it may concern:

Be it known that we, MORTIMER BYE and LEWIS H. CARLSON, citizens of the United States, residing at Detroit, in the county of 5 Wayne and State of Michigan, have invented certain new and useful Improvements in Medicinal Preparations, of which the following is a specification.

As is well known, the muscles of the body 10 are divided into two general classes commonly referred to as "striped" and "unstriped" muscles. The "unstriped" or "smooth" are the involuntary muscles of the body, that is, those that are not ordinarily 15 controlled by the will but operate automatically. Heretofore the pain or spasm of such muscles has been controlled or relieved chiefly by the administration of narcotics, which tend to seriously affect the vital 20 functions of the body and frequently lead to the formation of "habits" of "drug addictions." The object of our said invention is to provide a medicinal agent for the treatment of pain or spasm caused directly or indirectly 25 by the "unstriped" or "smooth" or "involuntary" muscles which will be very efficient in its action, harmless in results, and without objectionable characteristics in its administration.

30 Such medicinal agent consists of a white, practically tasteless and odorless crystalline powder made by the action of benzyl alcohol on succinic acid, resulting in benzyl succinate of the formula

35 Said product is manufactured by the following process: We take, for example, 1600 40 grams of succinic acid and mix with 2700 cc. of benzyl alcohol in a 5-liter, round bottom, pyrex flask and connect the flask with a reflux condenser and place the flask in an oil bath. This bath is then heated to 185 45 to 195° C. The first bubbling appears at about 160° C. and at 180 to 185° C. there appears a lively boiling. The heat is maintained at 185 to 195° C. for about eight hours. It is then allowed to cool when there 50 will be found a deposit of unreacted succinic acid which is then filtered off. The filtrate is now subjected to a vacuum distillation. The material which remains in the flask above 200° C. at 15 mm. pressure 55 is saved. The material in the receiving flask

contains water, unreacted benzyl alcohol, and succinic acid. Thus far the process has not been unknown but has not been used for practical purposes, and does not result in a purified or practical medicinal product 60 for such purposes as ours is intended to be used for. At this point we transfer the material from the flask to a 1,000 cc. beaker and 5 per cent or more of its volume of a foreign solvent such as alcohol or other appropriate solvent is added. It is then allowed to freeze by placing the beaker in an ice bath. It is then stirred and the benzyl succinate will crystallize out. The material in the beaker will become a mass of crystals. 70 It is then filtered by suction or pressure and the benzyl succinate allowed to dry in the open. After the benzyl succinate is dried in the open, it becomes necessary to recrystallize again from alcohol or other appropriate solvent. This process with the materials stated will produce a yield of about 1620 grams of benzyl succinate. 75

It will be understood, of course, that the process described may be modified in any 80 manner that may be found practicable to produce the described product, the process here outlined being one that we have practiced and found entirely suitable for the purpose. 85

Having thus fully described our said invention, what we claim as new and desire to secure by Letters Patent, is:

1. The method of producing benzyl succinate in the form of crystalline powder 90 which consists in treating succinic acid with benzyl alcohol, heating the same, then filtering, then adding a foreign solvent, then freezing, then drying.

2. The method of producing benzyl succinate in the form of crystalline powder 95 which consists in treating succinic acid with benzyl alcohol, heating the same, then filtering, then distilling by vacuum, then adding a foreign solvent, then crystallizing by freezing, then filtering, then drying, then recrystallizing, and then drying. 100

3. The method of producing a medicinal agent in the form of crystalline powder 105 which consists in treating succinic acid with benzyl alcohol and then reducing to the form of powder by a method which includes concentration and then dilution in a foreign solvent crystallization by freezing, substantially as set forth. 110

4. The method of producing a medicinal agent in the form of crystalline powder which consists in treating succinic acid with benzyl alcohol and reducing to the form of a dry powder by a method which includes first heating, and then diluting by the addition of a foreign solvent, then crystallizing by freezing, and then drying, substantially as set forth.

In witness whereof, we have hereunto set our hands and seals at Detroit, Michigan, this 4th day of June, A. D. nineteen hundred and twenty-one.

MORTIMER BYE. [L. S.]
